UNITED STATES PATENT OFFICE

2,627,657

FABRIC CUTTER GUARD

Fred L. Etchen, Detroit, Mich., assignor to L. A. Young Spring & Wire Corporation, Detroit, Mich., a corporation of Michigan

Application August 27, 1951, Serial No. 243,777

6 Claims. (Cl. 30—264)

1

This invention relates to improvements in fabric cutter guards.

The main objects of this invention are:

First, to provide guards for fabric cutters of the type which are translated over the work on which the pattern has been marked or outlined or superimposed.

Second, to provide a fabric cutter of this type with an effective guard which permits vision of the cutter and the work as the cutter is translated over the work.

Third, to provide a fabric cutter in which the guard may be adjusted to and from the shoe and also tiltingly adjusted.

Objects relating to details and economies of the invention will appear from the description to follow. The invention is pointed out in the claims.

A preferred embodiment of the invention is illustrated in the accompanying drawings, in which:

Fig. 1 is a perspective view of a cutter embodying my invention.

Fig. 2 is a plan view of the guard removed from the cutter, the supporting post being shown in sections.

Fig. 3 is a fragmentary front elevational view showing the relation of the guard to the motor housing on which it is mounted.

Fig. 4 is an enlarged fragmentary view partially in section showing structural details of the guard.

The embodiment of my invention illustrated comprises a shoe 1 adapted to be translated over the work, rollers 2 being conventionally illustrated. The shoe is provided with a slot 3 through which the cutter disc 4 projects. The upright 5 is of forwardly facing U or channel section and is fixedly secured to the shoe and provided with a rearwardly projecting handle 6 by which the cutter is manipulated. The motor is designated generally by the numeral 7 and is carried by the upright, details of the mounting not being illustrated or the driving connection with the cutter disc. These parts are conventional and form no part of my invention except in combination with other parts.

The embodiment of the cutter guard of my invention illustrated comprises a bottom guard plate 8 which is slotted at 81 to embrace or receive the cutter disc 4 and the upright 5. The guard plate projects a substantial distance at the front of the cutter disc. Side guard plates 9 are disposed upon and secured to the bottom guard plate 8 as by means of the screws 10 inserted from the under side of the bottom guard plate. The side

2

guard plates are spaced inwardly from the side edges of the bottom guard plate. These side guard plates overlap portions of the upright 5 and project forwardly beyond the cutter disc. A post 11 is secured to the bottom guard plate as by the screw 12 to project upwardly in a rearwardly inclined relation to the bottom guard plate and between the front edges of the side guard plates. This post is in alignment with the cutter disc and constitutes a front guard element therefor.

This guard is mounted for vertical and tilting adjustment by means of brackets 13 and 14 which have opposed recesses 15 and 16, respectively, to receive the downward extension 17 on the motor housing. The brackets 13 and 14 are secured to the under side of the housing by screws 18 received in the holes 19 (see Figs. 2 and 3). The brackets 13 and 14 have depending arms 20 provided with longitudinal slots 21 receiving the screws 22 engaging the side plates of the guard. A further support is provided in the adjustable bracket 23 secured to the housing to project forwardly therefrom, the bracket including a tiltingly adjustable member 24 having a slot 25 therein receiving the screw 26 by means of which the post is clamped to the bracket. This permits vertical and tilting adjustment of the guard relative to the cutter disc.

The guard plates 8 and 9 are formed of transparent material such, for example, as the material commercially known as "plexiglas" so they do not obstruct vision of the shoe or the cutter disc or of the work which commonly has a pattern outlined or superimposed thereon or is provided with some other means indicating the cutting lines. Usually several layers of fabric to be cut are disposed in superimposed relation. The adjustability of the guard permits adaptation to different cutters or to meet the particular requirements of the user. The cutter disc is effectively guarded but at the same time the view is not obstructed. If desired, the forwardly projecting end of the guard base plate 8 may be grasped to assist in guiding the cutter and at the same time the cutter disc is effectively guarded.

I have illustrated and described my invention in a highly practical embodiment thereof. I have not attempted to illustrate or describe other embodiments or adaptations to particular cutters as it is believed that this disclosure will enable those skilled in the art to embody or adapt my invention as may be desired.

Having thus described my invention, what I claim as new and desire to secure by Letters Patent is:

1. In combination with a fabric cutter includ-

ing a shoe, an upright on said shoe, a motor including a housing carried by said shoe and a disc cutter having driving connection with said motor and disposed at the front of said upright with its rear edge guarded thereby, of a cutter guard comprising a bottom guard plate slotted to receive said cutter disc and upright and projecting forwardly beyond the cutter disc, laterally spaced side guard plates disposed on opposite sides of the cutter with their bottom edges secured to the bottom guard plate and with their front edges projecting forwardly beyond the cutter disc, brackets carried by said upright and having vertically slotted arms disposed on the outer sides of said side guard plates, screws engaging said slots for adjustably supporting said side guard plates, a post on said bottom guard plate disposed at the front of said cutter disc and between said side guard plates, a slotted bracket mounted on said motor housing to project forwardly therefrom, and a screw engaging said slot for adjustably securing said post to said bracket, said guard mounting permitting vertical and tilting adjustment of the guard relative to the cutter disc, said bottom and side guard plates being of transparent material permitting vision of the cutter disc and the shoe and facilitating the manipulation of the cutter upon the work.

2. In combination with a fabric cutter including a shoe, an upright on said shoe, a motor including a housing supported by said shoe and a disc cutter having driving connection with said motor and disposed at the front of said upright with its rear edge guarded thereby, of a cutter guard comprising a bottom guard plate slotted to receive said cutter disc and upright and projecting forwardly beyond the cutter disc, laterally spaced side guard plates disposed on opposite sides of the cutter with their bottom edges secured to the bottom guard plate and with their front edges projecting forwardly beyond the cutter disc, brackets supported by said upright and having vertically slotted arms disposed on the outer sides of said side guard plates, screws engaging said slots for adjustably supporting said side guard plates, said guard mounting permitting vertical and tilting adjustment of the guard relative to the cutter disc, said bottom and side guard plates being of transparent material permitting vision of the cutter disc and the shoe and facilitating the manipulation of the cutter upon the work.

3. In combination with a fabric cutter including a shoe, an upright on said shoe of forwardly facing U section provided with a handle, a motor including a housing carried by said upright and a disc cutter having driving connection with said motor and disposed at the front of said upright

with its rear edge guarded thereby, of a cutter guard comprising a bottom guard plate slotted to receive said cutter disc and upright and projecting forwardly beyond the cutter disc, and laterally spaced side guard plates disposed on opposite sides of the cutter with their bottom edges upon and secured to the bottom guard plate and with their rear edges overlapping the said upright and their front edges projecting forwardly beyond the cutter, said motor housing having guard supporting brackets thereon, said bottom and side guard plates being of transparent material permitting vision of the cutter disc and the shoe and facilitating the manipulation of the cutter upon the work.

5. In combination with a fabric cutter including a shoe, an upright on said shoe, a motor including a housing supported by said shoe and a disc cutter having driving connection with said motor and disposed at the front of said upright with its rear edge guarded thereby, of a cutter guard supported by said upright and comprising a bottom guard plate slotted to receive said cutter disc and upright and projecting forwardly beyond the cutter disc, and laterally spaced side guard plates disposed on opposite sides of the cutter with their bottom edges secured to the bottom guard plate and with their front edges projecting forwardly beyond the cutter, said bottom and side guard plates being of transparent material permitting vision of the cutter disc and the shoe and facilitating the manipulation of the cutter upon the work.

20 6. In combination with a fabric cutter including a shoe, a rotatably mounted cutter disc and a driving motor therefor supported by the shoe, of a cutter guard supported by the shoe comprising a bottom plate slotted to receive the cutter disc, and side plates disposed on opposite sides 25 of the disc, said guard being mounted for vertical and tilting adjustment relative to the cutter disc, said bottom and side guard plates being of transparent material permitting the work and the relation of the cutter thereto to be viewed through the guard.

30 7. In combination with a fabric cutter including a shoe, a rotatably mounted cutter disk and a driving motor therefor supported by the shoe, of a cutter guard supported by the shoe comprising a bottom plate slotted to receive the cutter disc, and side plates disposed on opposite sides 35 of the disc, said bottom and side guard plates being of transparent material permitting the work and the relation of the cutter thereto to be viewed through the guard.
